(57) **CLAIM**

The ornamental design of a rear combination lamp for a vehicle, as shown and described.

DESCRIPTION

FIG. 1 is a perspective view of the rear combination lamp for a vehicle of the present design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The design can be embodied with plastics, glass and metal. This rear combination lamp is arranged in the rear of the car. This design is characterized in the shape and configuration of the rear combination lamp for a vehicle.
